CARLOS T. PIERCE, OF NEWTON, MASSACHUSETTS

FIRE-PROTECTIVE AND ROOF-COOLING DEVICE

Application filed March 25, 1929. Serial No. 349,555.

This invention relates to improvements in fire-protective and roof-cooling devices for buildings, and the object thereof is to provide a device for projecting jets of water upon the roof of a house in such a manner as substantially to moisten the entire roof, thereby protecting an inflammable roof from ignition by burning brands from another building.

10 A further object of the invention is to provide a device of the character specified adapted to provide a flow of water across the roof which in dropping to the ground from the eaves thereof will provide a protective apron 15 for the sides of the building which will protect it from fire.

A further important object of the invention is to provide a device of the character described for moistening the roof of a building during hot weather so that the evaporation of the water from the roof will produce a very substantial cooling effect upon the roof and the air of the upper chambers of the house and also will cool the air in the 25 vicinity of the house.

A further object of the invention is to provide a fire-protective and roof-cooling device of the character specified made in sections which can be readily constructed and assembled.

A further object of the invention is to provide a construction comprising a sheet metal saddle board, for the ridge of a roof, formed in sections, each having rigid therewith a fluid-conducting conduit perforated at intervals to provide jet-producing orifices, with means for coupling the ends of the conduit sections together in such a manner as to assemble and maintain the adjacent saddle 35 board sections in overlapping relation.

A further object of the invention is to provide such a construction that the overlapping ends of adjacent sections of saddle boards will prevent water from flowing therebetween without the necessity of soldering or otherwise sealing the joint between the sections.

Another object of the invention is to provide such a construction that one of the sec-

tions of saddle board and conduit can be readily shortened if necessary or desirable.

Another object of the invention is to provide saddle board sections each having a plurality of pipe-receiving brackets, with means 55 for rigidly securing the pipe to the respective brackets.

Another object of the invention is to provide a housing for the pipe with suitable means for securing the housing to the pipe- 60 supporting bracket.

These and other objects and features of the invention will more fully appear from the following description and the accompanying drawings and will be particularly pointed out in the claims.

In the drawings:

Fig. 1 is a perspective view of a house having applied thereto a fire-protective and roof-cooling device embodying the invention;

Fig. 2 is a detail view illustrating a plurality of saddle board sections having rigid therewith a fluid-conducting conduit perforated at intervals and illustrating a preferred 75 means for connecting adjacent sections of the conduit together, with the ends of the saddle boards in overlapping relation;

Fig. 3 is an elevation showing two saddle board sections with the fluid conducting conduits secured thereto in separated position, with a coupling intermediate of the conduit sections adapted to assemble the sections in overlapping relation, as illustrated in Fig. 2;

Fig. 4 is a side elevation showing a suitable housing or covering for the conduit; and,

Fig. 5 is a detail view illustrating preferred means for supporting the conduit upon the saddle board and the housing upon the conduit.

A preferred embodiment of the invention is illustrated in the accompanying drawings applied to a building such as a factory, office building or dwelling and comprises a saddle board which is mounted on the ridge of the roof and which is formed in sections each of which is provided with a pipe section forming a fluid-conducting means extending longitudinally of the saddle board section and perforated at intervals with suitable means

coupling the adjacent ends of sections together in such a manner that the end of one saddle board section overlies the adjacent end of another.

5 The saddle board is formed in sections 1, desirably of sheet metal, preferably copper, of inverted V-shaped cross section and having the required angularity to correspond to the pitch of the roof.

10 One end of each section, which may be termed the front end 2, desirably is mitred or cut on an angle rearwardly from the apex 3 of the saddle board. The opposite end 4 of each section of the saddle board desirably 15 is cut at right angles to the apex or ridge of the section. Each saddle board section is provided with fluid-conducting means such as a pipe section 5 which may be secured to the saddle board section in any suitable manner.

In the preferred construction illustrated herein the saddle board section is provided with a plurality or series of brackets having a circular pipe-embracing section 6 and 25 downwardly extending legs 7 diverging from each other at the same angle as the sides of the saddle board section 1. The legs of the brackets may be secured to the saddle board section in any desired manner as by bolts 8 or soldering 9. The circular portions 6 of the brackets are in alinement and desirably are vertically over the apex or ridge of the saddle board.

35 The pipe sections are provided with a series of narrowly spaced apertures 10 located in the lower portion of the pipe and so positioned as to direct jets of fluid from the pipe upon or in substantial parallelism with the faces of the saddle board 1.

40 In order properly to position the pipe and prevent rotation thereof about its axis, means desirably are provided for securing the pipe to the brackets 6. Any suitable means may be employed. The preferred means illustrated herein comprises screws 11 which extend through suitable apertures in the brackets and are seated in screw threaded walls of apertures in the pipe 5. The screws 11 may also be employed to secure a cover or housing 50 upon the brackets as shown in Figs. 4 and 5 for purposes which will hereinafter appear.

The front end 12 of the pipe section 5 desirably terminates short of the front end 2 of the saddle board section and is provided with 55 a screw threaded end. The rear end 13 of the pipe desirably extends beyond the rear end 4 of the saddle board and is provided with screw threads of opposite pitch to those upon the front end 12. The front and rear 60 ends of adjacent pipe sections are coupled together by a nipple or coupling 14 provided at its respective ends with internal screw threads of reverse pitch which are complementary to the threads of the front and rear 65 ends 12 and 13 of the pipe sections. When,

therefore, the coupling 14 is applied and screwed up, the adjacent ends of the saddle board sections will be drawn into telescoping arrangement.

Desirably the bevel of the front end of 70 each saddle board section is such that when the nipple is screwed up it will overlap the rear end of the adjacent section sufficiently to bring the squared end well behind the bevelled front end, so that any fluid which is 75 projected upon the overlying front end of the saddle board section will run down upon the face of the overlapped section and be shed from such face without danger of causing an accumulation of the fluid which will cause it 80 to enter between the adjacent faces of said sections and to flow around the squared rear end of the overlapped section. By thus bevelling the end of the overlapping section, 85 water is prevented from accumulating between the lower face of the overlapping section and the one beneath it which in cold weather would freeze and turn up the corner 90 of the section as may be observed in usual V-shaped saddle board constructions.

95 It has heretofore been pointed out that it is desirable that the rear end of each section shall extend at right angles to the apex or ridge of the section and that the rear end 13 of the pipe shall extend beyond the rear end of the section. This is particularly desirable in order that the rear end of any section may be cut off when necessary or desirable to finish the saddle board flush with the end of the ridge of the roof.

100 By virtue of such construction the saddle boards with the attached pipes or conduits may be constructed in sections of standard length and if, when assembled upon a roof, the rear end of the saddle board projects beyond the end of the ridge of the roof, it may be sheared off flush with the end of the roof and the pipe thereafter sawed off by a hack saw, or otherwise, and screw threaded with a common screw threading tool to receive a coupling for a conduit for supplying water to the pipe or to receive an internally screw threaded cap to close the end of the pipe as the case may be.

105 Obviously the front end of the saddle board may also be cut off to receive a cap or a nipple or elbow leading to a water supply as may be desired.

110 When the device is to be assembled upon a house, as illustrated in Fig. 1, the first saddle board section 15 is applied to the ridge of the roof and secured thereupon by nails or otherwise. The second section 16 is then placed upon the roof. The coupling 14 is 115 then applied to the screw threaded rear end of the section 15 and the front end 12 of the section 16. Upon the setting up of the nipple or coupling 14, the front end of the section 15 will be caused to overlap the rear end of the saddle board 15. The overlapping sec- 120

tions may then be nailed to the roof. Other saddle board sections 17 and 18 with their respective pipe sections will be similarly assembled and secured to the roof to extend the full length thereof. A suitable nipple or fitting 19 may be connected to the rear end 13 of the pipe 5 and a suitable pipe or conduit 20, connected to the fitting 19, may extend downwardly in any convenient way as beneath the roof and downwardly adjacent a corner of the house where its lower end may be coupled with any suitable water-supplying means, such as a service pipe leading to a sill cock 21. The pipe 20 may be provided with a suitable valve 22 which may be opened when the sill cock 21 is closed, to supply water through the pipe 20 and fitting 19 to the distributing pipe or conduit 5 which extends along the ridge of the roof of the building.

When water under pressure is thus supplied to the conduit 5 it is projected from the pipe or conduit in small jets at uniform distances throughout the length of the roof and both sides of the roof thereof. Thus water may be distributed with substantial uniformity over practically the entire area of the roof.

The pressure and volume of the water may be controlled by the valve 22 so that a relatively small amount of water may be used when it is desired merely to cool the roof alone, or a much larger quantity may be discharged when it is desired to protect the roof from fire.

By discharging a large quantity of water from the pipe or conduit 5 a blanket of water may be caused to descend from the eaves of the roof, (if there is no gutter present), which will protect the side of the house from flames of an adjacent burning house. Furthermore, the sheet of water thus projected from the roof may be used in the summer to increase evaporation of moisture in the vicinity of the house for the purpose of cooling the surrounding air.

In some instances it may be desirable to provide the pipe or conduit 5 with a cover or housing which will act not only to conceal the pipe and provide a more pleasing appearance, but which will also to a great measure protect the jet orifices against the action of heavy wind. Such a housing 23 or covering is illustrated in Figs. 4 and 5 and comprises a plate of sheet metal bent into V-shape preferably corresponding substantially in angularity to the form of the saddle board. This cover or housing desirably is secured to the brackets 6 and may be conveniently connected thereto by the screws 11. In such case suitable tapering washers 24 may be placed between the cylindrical upper end of the bracket 6 and the under face of the cover or housing 23. Other washers 25 having re-entrant under faces and a flat upper face may be inter-

posed between the upper side of the housing 23 and the head 26 of the screw 11.

While the invention has heretofore been described as providing means for projecting water upon the roof for fire prevention purposes and for the purpose of cooling the roof and airing the vicinity of the building, it is obvious that it may be employed to conduct other fluids which may be more effective for extinguishing fires by providing a suitable coupling at the lower end of the pipe 20, or where a reservoir is located upon the top of the factory for fire prevention purposes, as is quite common, the inlet pipe 20 may lead from the reservoir with a suitable valve for controlling the delivery of water from the reservoir to the inlet pipe 20.

The presence of the sheet metal saddle board and the pipe upon the ridge of the roof with the metallic connection therefrom to the ground also provides in effect a lightning rod which will protect the roof of the building from being struck by lightning.

It will, therefore, be understood that the term "saddle board" is used herein in a broad sense to include not only a member having angularly disposed sides or flanges to embrace the ridge of the roof, but also angularly disposed members adapted to embrace the edge of a roof, such as a flat roof, or any other ridge or corner of a building.

While the fluid-conducting means illustrated in the accompanying drawings is in the form of a pipe or conduit which is carried by brackets upon the pipe section, it will be obvious that other forms of conduits may be employed and that such other forms of conduit sections may be otherwise attached to or formed integral with the saddle board section.

It will, therefore, be understood that the particular embodiment of the invention shown in the drawings is of an illustrative character and is not restrictive of the scope or meaning of the following claims.

Having thus described the invention, what is claimed as new, and desired to be secured by Letters Patent, is:

1. A fire-protective and roof-cooling device comprising a sheet metal saddle board, for the ridge of a roof, formed in sections each having a fluid-conducting conduit section rigidly mounted thereupon and extending longitudinally thereof and perforated at intervals, and means for coupling the sections of said fluid-conducting conduits together operable to retain said saddle board sections in overlapping assembled position.

2. A fire-protective and roof-cooling device comprising a V-shaped sheet metal saddle board formed in sections, each having a fluid-conducting conduit section rigidly mounted thereupon and extending longitudinally thereof and perforated at intervals and at one end terminating short of the same

- end of the saddle board, and means for coupling said conduit sections together operable to assemble and secure the adjacent ends of saddle board sections in overlapping relation. 10
3. A fire-protective and roof-cooling device comprising a V-shaped sheet metal saddle board formed in sections, each having a fluid-conducting conduit section rigidly mounted thereupon and extending longitudinally thereof and perforated at intervals and at one end terminating short of the same end of the saddle board, right hand and left hand screw threads upon the respective ends of the 15 conduit, and a nipple having its ends provided with right hand and left hand screw threads complementary to those of said conduit, and operable to couple said conduit sections together and to assemble and maintain said saddle board sections in overlapping relation. 20
4. A fire-protective and roof-cooling device comprising a V-shaped sheet metal saddle board formed in sections, one end of each section being squared with, and the other end beveled backwardly from, the ridge of the section, a plurality of brackets rigid with said saddle board, a pipe section perforated at intervals mounted in said brackets and terminating short of the beveled end of said saddle board section, and coupling means operable to connect the ends of pipe sections together and to assemble and maintain the beveled end of one saddle board section in 25 overlapping relation relatively to the squared end of another section. 30
5. A fire-protective and roof-cooling device comprising a V-shaped sheet metal saddle board formed in sections, one end of each section being squared with, and the other end beveled backwardly from, the ridge of the section, a plurality of brackets rigid with said saddle board, a pipe section perforated at intervals mounted in said brackets, extending longitudinally of said saddle board section and terminating short of the beveled end and extending beyond the squared end of said saddle board section, and coupling means operable to connect the ends of the 35 pipe sections together and to assemble said sections with the beveled end of one section overlapping the squared end of another section. 40
6. A fire-protective and roof-cooling device comprising a V-shaped metal saddle board formed in sections, a plurality of brackets having legs rigidly secured to each of said saddle board sections and having pipe-receiving loops spaced from the ridge of said 45 saddle board, means securing said loops to said pipe, and means for coupling the ends of adjacent pipe sections together in longitudinal alinement. 50
7. A fire-protective and roof-cooling device comprising a V-shaped metal saddle 55 board formed in sections, a plurality of brackets having legs rigidly secured to said saddle board, pipe-receiving loops spaced from the ridge of said saddle board, an inverted V-shaped housing mounted on said brackets and covering said pipe, and coupling means for connecting adjacent pipe sections in longitudinal alinement operable also to assemble the ends of said saddle board sections and the ends of said housing 60 sections together in overlapping relation. 65
8. A fire-protective and roof-cooling device comprising a V-shaped metal saddle board formed in sections, a plurality of brackets having legs rigidly secured to said saddle board, pipe-receiving loops spaced from the ridge of said saddle board, an inverted V-shaped housing mounted on said brackets and covering said pipe, machine screws extending through the ridge of said 70 housing and the loops of said brackets therebeneath into said pipe sections, and coupling means operable to connect the ends of said pipe sections together and to assemble the ends of the saddle board sections and the ends of said housing sections in overlapping relation. 75

CERTIFICATE OF CORRECTION.

Patent No. 1,831,880.

Granted November 17, 1931, to

CARLOS T. PIERCE.

It is hereby certified that error appears in the printed specification of the above numbered patent requiring correction as follows: Page 4, strike out lines 54 to 63, comprising claim 6, and for the ordinals of claims 7 and 8 read 6 and 7; and that the said Letters Patent should be read with these corrections therein that the same may conform to the record of the case in the Patent Office.

Signed and sealed this 16th day of February, A. D. 1932.

(Seal)

**M. J. Moore,
Acting Commissioner of Patents.**
